(57) **CLAIM**

The ornamental design for a universal toilet stools, as shown and described.

DESCRIPTION

FIG. 1 is a perspective view of the universal toilet stools for a toilet illustrating my new design in position adjacent a toilet;

FIG. 2 is a perspective view of a single stool of the universal toilet stools showing my new design;

FIG. 3 is a right side view of a single stool thereof, which right side view is an identical mirror image of the left side view thereof;

FIG. 4 is a front view of a single stool thereof;

FIG. 5 is a rear view of a single stool thereof;

FIG. 6 is a top view of the single stool thereof; and,

FIG. 7 is a bottom view of the single stool thereof.

The broken line showing the underside of the stool is included for the purpose of illustrating a portion of the toilet stool that forms no part of the claimed design.

The broken line showing a toilet is included for the purpose of illustrating environment that forms no part of the claimed design.
